UNITED STATES PATENT OFFICE.

OTTO MACKENSEN, OF JENA, GERMANY. ASSIGNOR TO THE FIRM OF CARL ZEISS, OF JENA, GERMANY.

SIGHTING DEVICE FOR AIRCRAFT.

Application filed August 13, 1921. Serial No. 492,110.

To all whom it may concern:

Be it known that I, OTTO MACKENSEN, a citizen of the German Empire, residing at Jena, Germany, have invented a new and 5 useful Sighting Device for Aircraft, of which the following is a specification.

The present invention relates to a device, provided with a downwardly directed sighting device, the sight line of which, by means 10 of an adjustable gearing (e. g. a curve-gearing), actuated by a uniformly running driving gear (e. g. clock work), undergoes a change of inclination and which device serves for determining the moment of dropping projectiles from air-crafts, i. e. that 15 moment when the sight line reaches that position in which the angle, embraced by it and the vertical line, is equal to the dropping angle.

20 In the annexed drawing Fig. 1 is a diagrammatic view showing the schematic principles of the invention. Figs. 2 and 3 are vertical sections through a device according to the invention.

25 Fig. 1 of the said drawing may serve to elucidate the principle of the invention. AC denotes the trajectory of an air-craft, moving along at the height H at the speed v . According to the air-craft being at A or B or 30 C, the sight-line directed towards a target Z is inclined towards the vertical line at an angle φ or α , or zero. Let the angle α be the aiming off angle. In order that the sight-line will always remain directed at the target, it 35 is necessary to change the angle φ constantly, viz. according to the equation, easily to be derived

$$40 (1) \quad \frac{d\varphi}{dt} = \frac{v}{H} \cdot \cos^2 \varphi$$

The dropping angle α is determined by the equation

$$45 (2) \quad \operatorname{tg} \alpha = \frac{v\tau - R}{H}$$

50 in which case τ means the time, required by a projectile for dropping from the height H , and R denotes the back-drift which the projectile undergoes during this drop owing to the resistance of the air in the direction of flight. As the time required for dropping

is a function of the height H and as, furthermore, the value $\frac{R}{H}$ may be taken as invariable for a certain shape of the projectile 55 and an unchangeable actual speed of the aircraft, the equation 2 may be replaced by

$$(3) \quad \operatorname{tg} \alpha = \frac{v}{H} f(H)$$

From the two equations 1 and 3 it follows that for a certain value of the fraction $\frac{v}{H}$, on the one hand, the change of the angle φ 65 only depends on the angle φ itself and that on the other hand, the dropping angle α only changes with the height of flight H .

According to the invention the adjustable gearing of the device actuated by the uniformly running driving gear, is, on the one hand, connected with a movable part of the sighting device, determining the position of the sight-line e. g. a pivotally mounted prism in such a manner that the sight-line remains 70 automatically directed to a target to which it has been directed at the outset. Besides, the said gearing is so constructed that to each value of the fraction $\frac{v}{H}$ corresponds a 75 certain adjustment.

The adjustment of the gearing, which corresponds to the value of this fraction in each case, is suitably ascertained by means of trials, i. e. by being altered until the sight-line remains directed to the target. On the other hand, according to the invention the gearing is coupled to a second gearing, serving for the adjustment of the dropping angle in such a manner that the said second 85 gearing only needs an adjustment by hand in accordance with the height of flight H of the air-craft.

In order to make known the moment of dropping, any suitable arrangement may be 90 made, e. g. the motions of the sight line (the alterations of the angle φ) may, in a known way, be indicated by an index on a scale graduated according to angular values, the dropping angle α being indicated by a 95 second index on the said scale.

However, such an indicator-device may be

dispensed with, if provision be made for an automatic release of the projectile dependent on the dropping angle and the position of the sight-line.

5 The advantage afforded by a device, equipped according to the invention, over other devices of this kind consists in the feature, that on the one hand, the sight-line remains automatically directed to a target and
 10 that, on the other hand, owing to the two gearings being coupled to each other, the dropping angle can be ascertained in a particularly simple way.

If a sighting telescope be used as a
 15 sighting device, it is advisable, with a view to attain the largest possible inclinations of the sight line towards the perpendicular line, to dispose the sighting-mark of the telescope unadjustably and to effect the adjustment of the sight-line by rotating a reflector system, disposed in front of the objective.

An advantageous kind of construction may be attained by providing each of the
 25 two gearings with a cam, viz, the gearing actuated by the driving gear with a cam which is uniformly rotated by the driving gear and adjustably disposed in the direction of its axis of rotation

30 according to the fraction $\frac{v}{H}$, and the gearing serving for the adjustment of the dropping angle with a cam, disposed in such a way as to be able to undergo two adjusting
 35 motions, viz, on the one hand, a rotation and, on the other hand, a displacement in the direction of its axis of rotation, one of these motions taking place automatically, owing to the two gearings being coupled to each other, when adjusting the cam appertaining to the other gearing.

In order to be able to alter quickly the inclination of the sight-line within wide limits, without impairing the motion given to the
 45 sight-line by the driving gear which, e. g., is desirable in order to require, in case of an intended change of the target after having regulated the drive of the sight-line, another regulation of the said drive, the driving gear may be fixed to a rotatably supported bush which forms the bearing for the cam adjusting the sight-line and the axis of rotation of which coincides with that of the said cam; a rotation of the bush then results in another rotation of the cam, independent of the rotation effected by the driving gear.

Figs. 2 and 3 of the annexed drawing show a device according to the invention in
 60 which a sighting telescope is used as a sighting device. Fig. 2 is a vertical section of the device which contains the optical axis of the telescope and Fig. 3 is another vertical section.

65 The telescope is a terrestrial one. Of its

optical parts only the objective a^1 rigidly supported inside the telescope casing a and a prism system disposed in front of this objective are visible. The said prism system is composed of two isosceles, rectangular prisms, one of which, a^2 , is rigidly disposed in the casing a , whilst the other a^3 , mediating the entrance of light, is so disposed in a bush b , rotatably supported in the casing a , the axis of rotation of which bush intersects the optical axis of the telescope and which is vertical to the plane containing the optical axis, that the reflecting surface of the said prism contains this axis of rotation. The rigidly disposed prism a^2 is connected to another isosceles, rectangular prism a^4 in such a manner that the hypotenusal surfaces of both prisms coincide, thus allowing of observing at the same time a sighting mark c^1 , traced upon a glass plate c with an object visible by means of the prism a^3 . The said sighting mark is supported after the Cardan principle in such a way that the centre of the bearing coincides with the front principal point of a collective lens d and that its distance from the sighting mark is equal to the focus of the said collective lens so that the sight-line determined by the sighting mark is always vertically directed.

The inclination of the ray of the sight-line can be varied by a rotation of the bush b . Such a rotation is effected by raising and lowering a wire e , actuating at its bottom and a yoke e^1 , the two arms of which are connected by means of a joint to one each of two arms b^1 fixed to the bush b . Besides, a spring b^2 , fitted to the casing a and to the bush b always tends to bring the latter into that terminal position, in which the position of the prism a^3 corresponds to the largest amount of aiming off of the sight line. The raising and lowering of the said wire e is effected by a rotation of a lever f^1 actuating at the top end of the wire, the said lever being wedged to a shaft f^0 , rotatably supported on the casing a . The said shaft is actuated by a rotation of the bell crank f^2 , f^3 , the one arm of which f^2 is fixed to the shaft f^0 whilst the other f^3 is in contact with a cam g . The latter is rotatably supported in a support h , slidably mounted between two guide members a^0 on the casing a and displaceable parallel to the chief axis of the telescope, in such a manner that its axis of rotation is parallel to the direction of displacement of the supporting body. The casing i contains a clockwork of which the shaft is denoted i^1 and the winding-up button by j and which by means of a shaft i^2 gives the cam g , a uniform, when viewed from above, counterclockwise rotation. With a displacement of the support h the shaft i^2 may slide along a spring g^1 of the cam by a groove g^2 . The clockwork casing i is fixed to a bush k , rotatably disposed at the

casing a , the axis of rotation of the said bush coinciding with that of the cam g . This bush forms the bearing of a shaft l , which may be rotated by means of a knob l^1 and on which a toothed wheel l^2 is fastened engaging in a circular rack h^1 of the support h , the teeth of the said gearing running round the said body h . The cam g is constructed in such a way, that in its highest position, corresponding to the largest, adjustable value of the quotient from the speed and the height of flight of the aircraft, viz, the fraction $\frac{v}{H}$, with a complete 15 revolution by means of the clockwork such a rotation of the prism a^3 is effected, that the angle of inclination of the sighting ray towards the vertical line φ varies from about 70° to 0° . In the lowest position of 20 the cam, corresponding to the smallest, adjustable value of the said quotient, an alteration of this angle φ from about 40° to 0° takes place. To the value of the angle φ adjusted in each case, corresponds a certain position 25 of the arm m^1 of a bell crank m^1, m^2 , which is rotatably disposed on the casing a about an axis parallel to the shaft f^0 in such a manner, that the free end of the arm m^1 will be 30 visible through the ocular of the sighting telescope.

The bell crank is adjusted with the aid of a lever f^4 fixed to the shaft f^0 , with which its arm m^2 is in contact by means of a slit guide. The support h also forms the bearing of a second cam n , which participates in the same way as the cam g is the displacements of the support h and which is so disposed as to engage by a groove n^1 in a spring o , fixed to a rotatably disposed shaft o^1 , the axis of rotation of which coincides with that of the cam g , and along which it may slide when the support h is displaced. The shaft o^1 can be rotated by means of a driving knob o^2 and an index o^3 indicates 45 the value of the rotation on a scale a^5 , graduated according to heights of flight. The cam n is connected with the arm p^1 of a bell crank p^1, p^2 , the arm p^2 being fixed to a shaft p^0 , which is parallel to the shaft f^0 and rotatably supported on the casing a . Moreover, the cam n is so constructed that, when being placed into such a position that the index o^3 indicates on the scale a^5 the height of flight H in each case and the adjustment of the support h corresponds to 50 the value of the fraction $\frac{v}{H}$ in each case, the position of the shaft p^0 corresponds to the dropping angle α , required for dropping a projectile at the said speed v and the said height H of the air-craft. To the value adjusted in each case of the dropping angle α corresponds a certain position of 55 the arm q^1 of a bell crank q^1, q^2 , which similar to the angle lever m^1, m^2 is rotatably

disposed on the casing a about an axis parallel to the shaft p^0 in such a manner that the free end of the arm q^1 will also be visible through the ocular of the sighting telescope. The bell crank q^1, q^2 is adjusted 70 by means of a lever p^3 , fixed to the shaft p^0 , with which its arm q^2 is connected by a slit guide. The arms m^1 and q^1 of the two angle levers are disposed close together so that the relative position of their free ends 75 can be observed.

In the annexed drawing the single parts of the device assume a position corresponding to an average value of the fraction $\frac{v}{H}$, 80 to an angle φ of the sighting ray relative to the vertical line of 0° and to a dropping angle α of about 20° . In order to be used, the device must be fixed to an air-craft in such a manner that with a horizontal position of the air-craft its chief axis is vertically directed. Thereupon the clockwork is to be actuated, and by rotating the bush h about its axis of rotation the cam g and at the same time the prism a^3 should be 90 adjusted in such a manner that the image of the sighting mark c^1 coincides with that of a target to be hit by a shell and, moreover, it is necessary to adjust the support h , by rotating the driving knob l^1 , in such 95 a way that these two images also remain coincident. By then adjusting with the aid of the driving knob o^2 the cam n in such a manner that the index o^3 indicates the height of flight of the air-craft on the 100 scale a^5 and consequently the arm q^1 of the bell crank q^1, q^2 assumes the position corresponding to the requisite dropping angle it will only be necessary to observe when the free end of the arm m^1 of the bell crank 105 m^1, m^2 coincides with that of the arm q^1 . At the moment when the arm m^1 has reached the said position, the projectile should be dropped.

I claim:

1. In a downwardly directed sighting device for air-crafts an adjustable gearing, a uniformly running driving gear actuating this gearing, part of the sighting device being movable and adapted to affect the position of the sight line of the device, means for connecting the said gearing to the said movable part, the latter part, on being adjusted according to the height of flight and speed in each case, being adapted to keep the 110 sight line automatically directed to the target, and means for coupling the said gearing to another one adapted to adjust the dropping angle in order to change automatically the position of the said gearing, when adjusting the said first gearing, in such a way as to require only one adjustment by hand according to the height of flight of the air-craft.
2. In a downwardly directed sighting de- 130

vice for air-crafts an adjustable gearing, a uniformly running driving gear actuating this gearing, a cam undergoing a uniformly revolving motion by the said driving gear and being adjustable in the direction of its axis of rotation, the said driving gear being fixed to a bush rotatably supported on the carrier of the said sighting device and serving as a bearing of the said cam so that,

on the bush being rotated, both the cam and ¹⁰ the driving gear are rotated as well and that the cam undergoes a further rotation, independent of that effected by the said driving gear.

OTTO MACKENSEN.
